LETTER

Benjamin H. Adler, Chicago, Ill.

Application October 13, 1933, Serial No. 693,426

4 Claims. (Cl. 40—140)

This invention relates to letters for signs, such as advertising signs, and has for its object to provide a new and improved device of this description. The invention has as a further object to provide a letter which can be easily and quickly inserted and removed from a combination of letters. The invention has as a further object to provide a letter with means for efficiently supporting the glass in connection therewith. The invention has as a further object to provide letters with connecting lugs for easily connecting them with adjacent letters. The invention has as a further object to provide means for preventing the moisture from passing out in front of the letter. The invention has other objects which are more particularly pointed out in the accompanying description.

Referring now to the drawing,

Fig. 1 is a front view of one of the letters; Fig. 2 is a rear view of the letter illustrated in Fig. 1;

Fig. 3 is a sectional view taken on line 3—3 of Fig. 2;

Fig. 4 is a sectional view taken of line 4—4 of Fig. 2;

Fig. 5 is a rear view of a letter showing a modified construction;

Fig. 6 is a sectional view taken on line 6—6 of Fig. 2;

Fig. 7 is a view in part section showing the meeting edges of two letters when placed together.

Like numerals refer to like parts throughout the several figures.

Referring now to the drawing, I have illustrated a letter 1 which, for purposes of illustration, I have shown as the letter E. This letter is preferably mounted or cast and may be made out of metal or any other suitable material. The letter is provided with a body portion 2 and is preferably provided with a raised portion 3 around the outline of the letter. At one side the letter is provided with a projecting connecting member 4 having its outer face in a plane back of the front plane of the letter. At the other side of the letter there is provided the recessed connecting lugs 5. The connecting member 4 passes under the connecting lugs 5 so that the two letters are held together. The letter has at the bottom a support engaging member 6 which fits over a support in the frame in which the letters are mounted. The letter has some suitable means for holding a glass in position back of it.

As shown in Fig. 2 there are four recessed lugs 5 on the back of the letter, there being two lugs 7

and 8 at the top and two lugs 9 and 10 at the bottom. The lugs at the top have recesses 11 which extend vertically entirely therealong. The lugs 9 and 10 have recesses 12 which are only open at the top and the inner ends, being closed at the bottom and the outer ends. The glass can be slid down from the top between the lugs 7 and 8 and will rest at the bottom of the recesses in lugs 9 and 10. On the back of the letter projecting inwardly from the back face of the letter 10 is an upstanding rib 13. This rib preferably engages the outer face of the glass and also acts to guide water that may run along the back of the letter, due to rain or the like, from getting on to the front of the letter. This upstanding rib 13 has passageways 14 therethrough at certain points, as indicated in Fig. 2, so that water which may enter from the front through the opening of the letter itself will be directed away from the front of the rib to the rear thereof so that it cannot get back on to the front of the letter.

In the construction of Fig. 2 there is a separate piece of glass back of the opening in each letter. In the construction shown in Fig. 5 the lugs 7, 8, 9 and 10 are omitted so that a single piece of glass may extend across several letters. When the letters are assembled the connecting member 4 of one letter is inserted in the recesses of the holding lugs 5, the two letters having overlapping portions at this point. The present construction makes an easy, simple, cheap and efficient manner of forming and connecting the letters, and also an effective manner of preventing water that may reach the back of the letter from running out on the front of the letter and streaking or staining it.

I claim:

1. A section to be used in signs comprising a body portion having at one edge a connecting piece with its front face back of the front face of the section and at its opposite edge separated recessed connecting lugs on the back of the body portion and extending toward the last mentioned edge, to receive the connecting piece of the adjacent section, said connecting lugs lapping the body portion of the section so that the connecting piece of the adjacent section has confining portions on both sides thereof.

2. A section to be used in signs comprising a body portion having at one edge a connecting piece with its front face back of the front face of the section and at its opposite edge separated recessed connecting lugs on the back of the body portion and extending toward the last mentioned edge, to receive the connecting piece of an ad-

5 adjacent section, one lug located near one end of the section and the other located near the other end of the section, the lugs being integral with the body portion of the section, the connecting piece of the adjacent section being received between the body portion and the lugs of the first mentioned section.

10 3. A section to be used in signs comprising a body portion having at one edge a connecting piece with its front face back of the front face of the section and at its opposite edge separated recessed connecting lugs on the back of the body portion and extending toward the last mentioned edge, one near each end of the section to receive the connecting piece of an adjacent sec-

tion, the face formed between the body portion and the recess of the lug being substantially in the same plane as the rear face of the body portion of the section.

15 4. A letter of cast material comprising a body portion formed to represent the letter, having at one edge a connecting piece with its front face back of the front face of the letter, and at its opposite edge separated recessed connecting lugs on the back of the body portion and extending toward the edge of that portion and lapping the body portion of the letter, to receive the connecting member of an adjacent letter.
